JACOB SANDLER, OF BOSTON, MASSACHUSETTS, ASSIGNOR, BY MESNE ASSIGNMENTS,
TO J. L. HINCKLEY, OF BOSTON, MASSACHUSETTS, AND C. D. KRUMSCHEID, OF NEW
YORK, N. Y.

INSTEP SUPPORT OR ARCH.

No. 888,936.

Specification of Letters Patent.

Patented May 26, 1908.

Application filed August 15, 1907. Serial No. 388,586.

To all whom it may concern:

Be it known that I, JACOB SANDLER, a citizen of the United States, residing at Boston, in the county of Suffolk and State of Massachusetts, have invented new and useful Improvements in Instep Supports or Arches, of which the following is a specification.

This invention relates to instep supports or arches which are applied and worn inside of boots or shoes for upholding the arch of the instep to prevent breaking down of the same, such as that shown and described in Letters Patent issued to me May 7, 1907 No. 852,625, on which the present invention is an improvement; and the object of the present invention is to provide an instep support of the character disclosed in the Letters Patent referred to with means, as hereinafter set forth, for reinforcing the metallic resilient stiffening plate to prevent the breaking thereof, and, further to increase or decrease the resiliency of certain portions of the stiffening plate when occasion so requires.

A further object of the invention is to provide a simple and effective reinforced instep support or arch prop of a yieldable nature to render it comfortable to the wearer and at the same time practical in performing its function without buckling or wrinkling the adjacent leather cover, or lining, as well as preventing breaking of the resilient stiffening plate.

With the foregoing and other objects in view, the invention consists in the novel construction, combination and arrangement of parts hereinafter more fully described and pointed out in the claims hereunto appended.

In the drawings, wherein like reference characters denote corresponding parts throughout the several views—Figure 1 is an inverted plan view of a reinforced instep support or arch prop in accordance with this invention; Fig. 2 is a longitudinal, sectional view on line 2—2 of Fig. 1, and, Fig. 3 is a transverse section on line 3—3 of Fig. 1.

Referring to the drawings, 1 designates a resilient metallic stiffening plate formed of any suitable material, but such that it will retain its shape or the shape desired and also give to the sole piece 2 the necessary arch to support the instep. The plate 1 has an edge contour conforming to that of the boot or shoe adjacent to the instep arch, and is riveted or otherwise fastened to the sole piece 2 as at 3. One side of the plate 1 has an up-

wardly-projecting or laterally-curved extension 4 which is so shaped as to conform, more or less closely, to the normal arch of the foot at the instep. This up-curved lateral extension is intersected by an outwardly-diverging slot 5 extending in a transverse direction and communicating at its inner end with a longitudinally-extending relief slot 6. The slot 5 allows for the compression of the plate and particularly the instep of the arch formed by the extension 4.

The depression of the entire plate by the weight imposed thereon causes the two edges 7, 8 of the slot 5 to draw nearer to each other and the inner relief slot 6 permits such movement of the edges of the slot 5 towards each other without liability of buckling or fracturing the intermediate part of the plate 1 so that the shape of the entire plate is maintained throughout its extent. The provision of the slots 5 and 6 also obviates breaking down of the plate, no matter what weight is disposed thereon. Furthermore the cutting away of the plate in the manner as set forth assists in returning the plate to its normal position after a maximum pressure thereon has been relieved. Therefore the shape of the instep of a boot or shoe is regularly preserved with comfort to the wearer and benefit to the boot or shoe structurally.

It will be seen that the plate is longitudinally arched, as well as laterally arched or upturned as just set forth and by this duplex arching of the plate the contour of a boot or shoe is rendered such as to fully conform to the natural shape of the foot.

To overcome liability of the plate breaking and to provide means whereby the plate 1 can be stiffened at certain portions throughout its length or width, a reinforcing member 9 is interposed between the plate 1 and the sole piece 2. The reinforcing member 9 is adjustably connected to the plate 1 through the medium of a headed stud 10, the shank 11 of which extends through the slot 6, the diameter of the shank being such that the member 9 can be longitudinally adjusted with respect to the plate 1 and sole piece 2. The member 9 is formed of suitable metallic material and is substantially concavo-convex in longitudinal section and with the edge thereof conforming in contour to that of the boot or shoe adjacent to the instep arch; or in other words the edge of the member 9 conforms substantially in contour to the edge of the plate 1.

2
 Owing to the interposition of the member 9 between the plate 1 and the sole piece 2 it is evident that such member acts as a reinforcing means to prevent the breaking of the plate 1 and that when said member is adjusted longitudinally with respect to the plate 1 it is evident that it acts as a stiffening medium for the plate 1 to prevent the bending thereof; or in other words, when moved clear of a portion of the plate 1 the resiliency of such portion will not be affected, but the resiliency of that portion of the plate which is engaged by the member will be affected owing to the fact that the plate 1 will be stiffened by engagement with the member therewith.

10 The reinforcing member 1 is not only longitudinally adjustable, but transversely adjustable as it is evident that the headed stud 10 can be positioned in the slot 5 so that a transverse adjustment of the reinforcing member can be had in order to stiffen the plate 1 at various portions throughout its length as will be evident. When the member 11 is transversely adjusted it is evident that it will act as a means to stiffen the split portion of the plate 1, such portion being formed by the slots 5 and 6.

15 What I claim is—

1. An instep support or arch prop comprising a stationary plate of resilient material, a sole piece conforming to an instep arch, means for securing the said stiffening plate

to the sole piece, and a reinforcing member interposed between the stiffening plate and the sole piece and adjustably connected to said stiffening plate.

2. An instep support or arch prop comprising a stationary plate of resilient material, a sole piece conforming to an instep arch, means for securing the said stationary plate to the sole piece, and a longitudinally and transversely-adjustable reinforcing member interposed between the stiffening plate and the sole piece.

3. An instep support or arch prop comprising a stationary plate of resilient material, a sole piece conforming to an instep arch, means for securing said stiffening plate to the sole piece, and a longitudinally and transversely-adjustable resilient reinforcing member interposed between the stiffening plate and the sole piece.

4. An instep support or arch prop comprising a sole piece conforming to an instep arch, a stiffening member carried thereby, and a longitudinally and transversely-adjustable reinforcing member for said stiffening member.

In testimony whereof, I affix my signature in presence of two witnesses.

JACOB SANDLER.
